UNITED STATES PATENT OFFICE.

WILLIAM McCALLUM, OF YONKERS, NEW YORK, ASSIGNOR TO THE
BIGELOW CARPET COMPANY, OF CLINTON, MASSACHUSETTS.

DESIGN FOR CARPET.

Specification forming part of Design No. 11,214, dated May 27, 1879; application filed April 8, 1879.
[Term of patent 3½ years.]

To all whom it may concern:

Be it known that I, WILLIAM McCALLUM, of Yonkers, Westchester county, New York, have invented a new and original Design for a Carpet, of which the following is a specification.

This invention relates to a new and original design for carpets, oil-cloths, and similar fabrics.

It consists of the ornamentation and arrangement of figures, hereinafter more fully pointed out.

The accompanying photographic illustration represents a face view of my newly-designed carpet.

The letter A represents the body of the carpet. B is the border thereof.

The background of the carpet is checkered, each of the small squares composing the checkered background containing small ornaments, many of which are of different description.

Upon the body A, traversing the checkered background, is represented a curved branch, a,

terminating in two branches, b c, and ornamented by flowers d and leaves e.

A number of branches of the same design as the branch a are represented upon the background, and are arranged in relation to each other as shown in the photograph, to produce my novel design.

The border B contains a substantial reproduction of the flowers d and leaves e between two stripes, f and g, both of which are richly ornamented, as shown.

I claim—

1. The design for a carpet, consisting of the branch a, branches b c, flowers d, and leaves e, substantially as shown.

2. The design for a carpet, consisting of the checkered background, and of the branches a, leaves e, and flowers d, substantially as shown.

WILLIAM McCALLUM.
